UNITED STATES PATENT OFFICE.

ALEC J. GERRARD, OF CHICAGO, AND LEROY F. HINTZ, OF HIGHLAND PARK, ILLINOIS;
SAID HINTZ ASSIGNOR TO SAID GERRARD.

BELT SQUARING AND PUNCHING MACHINE.

Application filed May 13, 1924. Serial No. 712,977.

To all whom it may concern:

Be it known that we, ALEC J. GERRARD and LEROY F. HINTZ, respectively a subject of the King of Great Britain and a citizen 5 of the United States, residing, respectively, at Chicago and Highland Park, in the counties of Cook and Lake and State of Illinois, have invented certain new and useful Improvements in Belt Squaring and Punching 10 Machines; and we do hereby declare the following to be a full, clear, and exact description of the invention, such as will enable others skilled in the art to which it appertains to make and use the same.

15 This invention relates to a belt squaring and punching machine and has for its object to provide a device of this character which will be simple in construction, comparatively inexpensive to manufacture, and more 20 efficient in use than those which have been heretofore proposed.

With these and other objects in view the invention consists in the novel details of construction and combinations of parts as 25 will be more fully hereafter disclosed and particularly pointed out in the claims.

Referring to the accompanying drawings, forming a part of this specification, in which like numerals designate like parts in all the 30 views,

Fig. 1 is a top plan view of a machine made in accordance with the invention;

Fig. 2 is a sectional view taken on the line 2—2 of Figure 1 and looking in the 35 direction of the arrow;

Fig. 3 is a sectional view taken on the line 3—3 of Figure 1 and looking in the direction of the arrow;

Fig. 4 is a partial sectional view taken on the line 4—4 of Figure 1 and looking in the 40 direction of the arrow;

Fig. 5 is a detail view of the cutter mounting; and

Fig. 6 is a diagrammatic view showing the 45 application of a belt fastener to a belt punched by a machine made in accordance with this invention.

In the drawings 1 represents a double-edged cutter rigidly secured to a lever-like 50 member 2 pinned or otherwise secured to the cutter shaft 3 which passes through an angular extension 4 of the supporting member 5 provided with the head 6 slidably mounted on the guide rod 7 supported be-

tween the extremities 8 and 9 of the cutter 55 frame 10, all as will be clear from Figures 1 and 4. The said cutter frame is provided with a downwardly extending portion 13 having on one side a vertical bearing surface 14 and on its opposite side a horizontally disposed groove or track 15 in which is slidably supported one end 16 of the cutter shaft 3. A handle 17 is secured to the opposite end of the said shaft 3 by which, it will be seen from Figures 1, 4 and 5, the 60 cutter 1 and its operating shaft 3 may be rotated as well as moved in either direction between the extremities 8 and 9 of the cutter frame 10.

A slot 20 is provided in the horizontally 70 disposed portion 21 of the cutter frame through which the double-edged cutter 1 may pass. Also located in the portion 21 is a row of spaced tapered holes 22, the 75 smaller diameter of said holes being lowermost as clearly seen in Figures 1 and 4. The purpose of these holes will be disclosed hereafter.

The belt receiving part of this mechanism comprises a base constituting the table 30 80 having its front edge squared to abut, and slide on, the flat bearing surface 14 of the cutter frame 10. Extending outwardly from the flat bearing surface 14 are two lugs 85 31 and 32 each bored to slidably receive respectively the pins 33 and 34 carried by the table 30 and which act to hold said table to the cutter frame all as will be clear from Figures 1 and 2. The said table 30 is of a width less than the space between the lugs 90 31 and 32 in order that the said table may be adjusted laterally as may be required and as will be explained later. This lateral movement of the table is accomplished by turning the adjusting knob member 35 which is so mounted on the extremity of the lug 32 that it will not move laterally therefrom but upon turning the said member 35 the table 30 will be moved toward or from the lug 32 by action of the worm 36 rigid with 95 35 and which is threaded into the body of the said table.

The table 30 is provided with the upstanding side edges or shoulders 40 which extend perpendicularly from the bearing surface 14 of the cutter frame and which constitute straight edges against which will be placed one side edge of the belt to be op-

erated upon, said shoulders 40 being longitudinally disposed at right angles to the slot 20 in the frame 10. These shoulders are extended as at 41 and 42 to provide 5 bases for the vertical posts 43 and 44 respectively.

The belt clamping portion of this device (see Figures 1, 2, 3 and 4) comprises the clamping bar 50 slidably mounted on the 10 posts 43 and 44 and provided with the upwardly projecting bearing lugs 51 and 52 adapted to be engaged by the bevelled under-surface of the square nuts or wedges 53 and 54 respectively. These wedges may 15 be moved towards or away from each other simultaneously by virtue of the fact that they are mounted on the right and left threaded worm shaft 55 having shouldered bearings 56 and 57 in the posts 43 and 44 20 and provided at one end with the hand wheel 58. The clamping bar is hollowed out as at 60 to a width to allow the sliding of the wedges 53 and 54 therein but not sufficient to allow rotation of the said wedges.

25 At the front side, the clamping bar is provided with the extension 61 in which is cut the elongated opening 62 and it will be seen from Figs. 1, 2 and 4 that the extreme forward edge of the extension 61 extends 30 nearly to the slot 20 through which operates the cutter 1. Interposed between the bases 41 and 42 and the overlying ends of the clamping bar 50 and adjacent the posts 43 and 44 respectively are the springs 65 and 35 66 suitably held against displacement and serving to hold the clamping bar in raised position. When the handle 58 is turned, however, the oppositely threaded worm 55 will cause the nuts or wedges 53 and 54 to 40 move away from each other, whereupon, due to the inclined or bevelled under-surfaces of the wedges, the contacting lugs 51 and 52 and therefore the entire clamping bar will be forced downwardly against the tension 45 of the said springs and ultimately clamp the belt beneath the bar 50 tightly to the table 30.

Referring now to Figures 1 and 2, 70 represents a belt punch provided with the usual 50 springs 71 and slidably mounted upon the guide rod 7 which forms the pintle of the hinge joint of said punch 70. The end of one of the punch jaws 72 is adapted to engage, and slide in, the groove or track 15. The other jaw 73 of the punch is provided 55 at its end with a bore through which may be passed the threaded neck portion of a cutting die 75 which may be conveniently fastened to the jaw 73 as by the lock nut or cap 76 engaging the protruding threaded portion of the said die. Riveted or otherwise 60 securely fastened to the jaw 73, and located about midway thereof, is a centering finger 77 extending downwardly or toward the other 65 jaw 72 and located in the plane of the two

said jaws. This finger 77 is longer than the punch die 75 and is curved in one direction, the center of curvature lying in the guide rod 7, or in other words, in the hinge of the punch 70. This finger 77 is adapted to 70 engage with one of the bevelled holes 22 and thereby position the punch 70 so that the holes punched in a belt by the die 75 will be spaced the same distance apart as are the holes 22. 80 is a hole in the lower jaw 75 72 through which the end of the centering finger may pass when the jaws 72 and 73 are brought together.

The punching die, as will be seen in Figures 1 and 2, is adapted to pass through the elongated opening 62 of the clamping bar 50 and, as stated above, will cut holes in a belt held by said clamping bar in accordance with the spacings of the holes 22 which the finger 77 engages. Therefore, the spacing 80 of the holes 22 is made the same as the spacing of the prongs 80 of the strip 81 of metal fasteners to be used for holding the ends 82 and 83 of the belt; see Figures 1 and 6. Further the relation of the parts 20, 50, 62 90 and 75 is such (see Figures 1, 2 and 6) that the row of holes 84 cut in the belt by the die 75 will be parallel to the slot 20 and spaced therefrom a distance equal to the distance from the middle point 85 of the strip of 95 fasteners to the downward bend 86 of each prong 80. Therefore, if the edge 87 of the end 83 of the belt to be punched lies along the slot 20 when the holes 84 are cut by the die 75, then the row of said holes will be 100 properly spaced from the edge 87 of the belt to receive the strip 81 of fasteners.

The operation of the device will be clear from the foregoing description but may be briefly summarized as follows: The belt is 105 slipped under the clamping bar 50 and positioned with a longitudinal edge thereof contacting a straight edge or shoulder 40. If the end of the belt is not square then the belt is slipped along the shoulder 40 until 110 the entire width of the belt overlies the slot 20. The wheel 58 is then turned to operate the wedges 53 and 54 which in turn force the clamping bar 50 down upon the belt. The double-edged cutter 1, and its associated 115 parts which during this procedure have been at either end of the slot 20, is now run across the machine to the opposite end of the said slot by means of the handle 17. To facilitate the cutting of the belt, the handle 17 should be actuated in short arcs 120 thus producing a cutting action of the "can-opener" type. After the cutter 1 has been thus operated, the end portion of the belt 125 will have been trimmed off squarely and with a true perpendicular cut.

In order that the holes to be punched in the belt may be approximately equidistant from the longitudinal or side edges thereof, the table 30 to which the said belt is clamped 130

is adjusted laterally to properly position the belt with reference to the finger guide holes 22 carried by the stationary cutter frame 10. This adjustment as heretofore disclosed 5 is accomplished by turning the knob 35 held by the cutter frame 10 thereby actuating the worm 36 threaded into the table 30. The knob 35 is turned until it is seen that the edges of the belt are respectively equi- 10 distant from the first hole 22 toward the opposite edge of the said belt.

The punch 70 is then moved along the guide rod 7 and operated so as to punch opposite each bevelled hole 22 the required 15 holes in the trimmed end of the belt. Then the hand wheel 58 is oppositely turned to move the wedges 53 and 54 toward each other whereupon the springs 65 and 66 will raise the clamping bar 50 off the belt, allowing 20 the punched end to be removed. The other end of the belt may then be inserted, positioned, clamped, cut, punched and removed in the same manner as above disclosed.

25 The usual shop method of trimming a belt is that of cutting the belt from its top surface by running a knife over and over again in a groove formed by the blade. This ordinarily is a laborious task and generally produces an edge which is not only not perpendicular to the surface of the belt, but which is sometimes as much as 30° to the said surface. By the use of this device such a situation is avoided, in that because 30 of the belt being tightly clamped and the peculiar construction of the knife blade operating as it does with a "can-opener" movement in a narrow slot, the knife is compelled to make a cut which is perpendicular to the surface of the belt. It will also be observed that this device will take not only 35 belts of various widths but this device will cut cleanly and quickly, belts of various thickness and compositions such as leather, 40 canvas, rubber, and balata.

The adjustment, which has been previously described for locating the extreme holes equidistant from the sides of the belt, provides a novel and unusual feature in that 45 after a series of round holes have been punched as heretofore described the table 30, with the belt clamped tightly thereto, may be shifted laterally to any extent desired and the punch reoperated with the result that the previously round formed holes may be formed into elongated or oblong holes. Also it is possible, after punching a series 50 of round holes as previously described, to loosen the clamping bar 50, shift the belt longitudinally on the table 30, reclamp the belt and reoperate the punch to produce an elongated hole extending longitudinally of the belt. From the foregoing, it will therefore be apparent that after a row of holes 55 has been punched, the table 30 together with

the belt may be moved laterally one half the distance between two adjacent holes, the belt then shifted longitudinally to a slight extent as previously described, and the punch reoperated to produce a second row 70 of holes in staggered relation to the first row of holes.

A further feature of the invention resides in the cutter die 75. That is to say, from Figure 2 it will be observed that the member 75 is provided with a threaded neck portion which extends through the jaw member 73 and is engaged by the cap screw 76 to hold the die 75 rigid with the said jaw. It is obvious that should holes of larger or 80 lesser diameter, according to the size of the belt or the size of fasteners used, be desired, a punch die of the desired diameter would be used to replace the die 75. In other words the punch die 75 is made easily 85 demountable from the punch jaw 73 for the purpose of replacement.

It is obvious that those skilled in the art may vary the details of construction as well as the arrangement of parts without departing from the spirit of the invention, and therefore it is not desired to be limited to the foregoing disclosure except as may be required by the claims.

What is claimed is:

1. In a belt squaring and punching machine the combination of a table; means to hold a belt on said table; means to cut square the end of the held belt; means to punch holes in the said belt; and means to 90 adjust the held belt relatively to the punching means.

2. In a belt squaring and punching machine the combination of a table; means comprising a clamping bar to hold a belt on 100 said table; means to cut square the end of the held belt; means to punch holes in the said belt; and means to adjust the held belt relatively to the punching means.

3. In a belt squaring and punching machine the combination of a table; means to hold a belt on said table; a pair of wedges to actuate said holding means; means to cut square the end of the held belt; means to punch holes in the said belt; and means to 110 adjust the held belt relatively to the punching means.

4. In a belt squaring and punching machine the combination of a table; means to hold a belt on said table; a pair of oppositely moved wedges to actuate said holding means; means to cut square the end of the held belt; means to punch holes in the said belt; and means to adjust the held belt relatively to the punching means.

5. In a belt squaring and punching machine the combination of a table; means to hold a belt on said table; rotatable and slideable means to cut square the end of the held belt; means to punch holes in the said belt; 120 125 130

and means to adjust the held belt relatively to the punching means.

6. In a belt squaring and punching machine the combination of a table provided with straight edges; means to hold a belt on said table against one of said straight edges; a frame slidably mounted on said table; means mounted on said frame to cut square the end of the held belt; means to punch holes in the said belt; and means to adjust the held belt relatively to the punching means.

7. In a belt squaring and punching machine the combination of a table provided with straight edges; means to hold a belt on said table against one of said straight edges; a frame slidably mounted on said table and provided with a slot disposed at a right angle to said straight edges; means mounted on said frame to cut square the end of the held belt; means carried by said frame to punch holes in the said belt; and means to adjust the held belt relatively to the punching means.

8. In a belt squaring and punching machine the combination of a table provided with straight edges; means to hold a belt on said table against one of said straight edges; a frame slidably mounted on said table and provided with a slot disposed at a right angle to said straight edges; means comprising a cutter associated with said slot and mounted on said frame to cut square the end of the held belt; means to punch holes in the said belt; and means to adjust the held belt relatively to the punching means.

9. In a belt squaring and punching machine the combination of a table provided with straight edges; means to hold a belt on said table against one of said straight edges; a frame slidably mounted on said table; means mounted on said frame to cut square the end of the held belt; slidable means carried by said frame to punch holes in the said belt; and means associated with said frame and table to adjust the held belt relatively to the punching means.

10. In a belt squaring and punching machine the combination of a table; means to hold a belt on said table; means to cut square the end of the held belt; means to punch holes in the said belt; and screw actu-

ated means to adjust the held belt relatively to the punching means.

11. In a belt squaring and punching machine the combination of means to cut square the end of a belt; means to punch a row of holes in said belt; and means whereby said belt and row of holes may be adjusted relatively to said punching means, whereby a second row of holes in staggered relation to the holes in said first row may be punched in said belt.

12. In a belt squaring and punching machine the combination of rotatable and slideable means to cut square the end of a belt; means to punch a row of holes in said belt; and means whereby said belt and row of holes may be adjusted relatively to said punching means, whereby a second row of holes in staggered relation to the holes in said first row may be punched in said belt.

13. In a belt squaring and punching machine the combination of a table; means to hold a belt on said table; means to cut square the end of the held belt; means slideable across said table, to punch holes in said belt; and means to adjust the held belt relatively to the punching means.

14. In a belt squaring and punching machine the combination of means to cut square the end of a belt; means to punch a row of holes in said belt; and means comprising a clamping bar and a screw whereby said belt and row of holes may be adjusted relatively to said punching means, whereby a second row of holes in staggered relation to the holes in said first row may be punched in said belt.

15. In a belt squaring and punching machine the combination of means to cut square the end of a belt; means to punch a row of holes in said belt; and means whereby said belt and row of holes may be laterally adjusted relative to said punching means, whereby a second row of holes in staggered relation to the holes in said first row may be punched in said belt.

In testimony whereof we affix our signatures.

ALEC J. GERRARD.
LEROY F. HINTZ.
